(57) **CLAIM**

The ornamental design for a bore cleaning tool, as shown and described.

DESCRIPTION

FIG. 1 is a perspective view of a longitudinal side and front axial end, according to a first embodiment thereof;

FIG. 2 is a perspective view of a longitudinal side and rear axial end, according to the first embodiment thereof;

FIG. 3 is a longitudinal side view thereof, according to the first embodiment thereof;

FIG. 4 is a front axial end view thereof, according to the first embodiment thereof;

FIG. 5 is a rear axial end view thereof according to the first embodiment thereof;

FIG. 6 is a perspective view of a longitudinal side and front axial end, according to a second embodiment thereof;

FIG. 7 is a perspective view of a longitudinal side and rear axial end, according to the second embodiment thereof;

FIG. 8 is a longitudinal side view thereof, according to the second embodiment thereof;

FIG. 9 is a front axial end view thereof, according to the second embodiment thereof; and,

FIG. 10 is a rear axial end view thereof according to the second embodiment thereof.

Except for the threads in the second embodiment, the bore squeegee is substantially symmetrical about its longitudinal axis. In the first embodiment, large broken lines illustrate a boundary of the claimed invention, and small broken lines illustrate environment, which forms no part of the claimed invention.
